DESIGN FOR A KITCHEN CABINET

Felippe A. Broadbent, Washington, D. C.

Application July 13, 1945, Serial No. 120,684

Term of patent 14 years

(Cl. D33—13)

To all whom it may concern:

Be it known that I, Felippe A. Broadbent, a citizen of the United States, residing at Washington, in the District of Columbia, have invented a new, original, and ornamental Design for a Kitchen Cabinet, of which the following is a specification, reference being had to the accompany drawings, forming part thereof.

In the drawings:

Fig. 1 is a perspective view of a kitchen cabinet illustrating my new design.

Fig. 2 is an end elevational view showing the sliding top member of the base unit in an extended position.

Fig. 3 is a front elevational view of the cabinet shown in Fig. 1.

I claim:

The ornamental design for a kitchen cabinet, as shown.

FELIPPE A. BROADBENT.
